UNITED STATES PATENT OFFICE

WILLIAM J. BRAY, OF WASHINGTON, DISTRICT OF COLUMBIA, ASSIGNOR TO GALLERIE
D'ART MODERNE, INC., OF WASHINGTON, DISTRICT OF COLUMBIA

DESIGN FOR A LAMP BASE

Application filed July 3, 1929. Serial No. 31,932. Term of patent 3½ years.

To all whom it may concern:

Be it known that I, WILLIAM J. BRAY, a citizen of the United States, residing at Washington, District of Columbia, have invented a new, original, and ornamental Design for a Lamp Base, of which the following is a specification, reference being had to the accompanying drawing, forming a part hereof.

The figure is a perspective view of a lamp base, showing my new design.

What I claim is:

The ornamental design for a lamp base, as shown.

WILLIAM J. BRAY.
